POSITIVE AND CONSTANT-TENSION WEB
LETOFF MECHANISM FOR TEXTILE MA-
CHINESGeorge E. Clentimack, Plainville, Mass., assignor
to Whitin Machine Works, Whitinsville, Mass.,
a corporation of Massachusetts

Application April 4, 1951, Serial No. 219,272

11 Claims. (Cl. 66—86)

1

This invention relates to mechanism for letting off a yarn or other web from a rotatable beam in a knitting, weaving or other textile machine. In such machines, it is essential that the yarn be fed to the knitting or other fabricating device as required to produce the desired product, and that the web be maintained under constant and substantially uniform tension while thus fed.

It is also essential that provision be made to compensate for the gradual reduction in the outside diameter of the yarn web on the beam from which it is supplied.

It is the general object of my invention to provide an improved mechanism for continuously and positively letting-off a web from a rotatable beam in a knitting or weaving or other textile machine.

A further object is to provide such let-off mechanism in which the operation is controlled by the differential between two opposing fluid tensions. I also provide improved means for varying the effective operating tension in predetermined relation to the gradual reduction in diameter of the web on the yarn or other supply beam.

The entire mechanism is mechanical and hydraulic, and all electrical, electronic or other similar complications are avoided. I also avoid delays in response to yarn tension changes, and defects in the appearance of the product which might be caused by starting, stopping or speed variation in the driving mechanism of the machine.

My invention further relates to arrangements and combinations of parts which will be herein-after described and more particularly pointed out in the appended claims.

A preferred form of the invention is shown in the drawings, in which:

Fig. 1 is a side elevation of the upper portion of a machine embodying my invention;

Fig. 1a is a similar view of a lower portion of the same machine;

Fig. 2 is a side elevation of the let-off or control unit; and

Fig. 3 is a sectional plan view, taken along the irregular line 3—3 in Fig. 2.

Referring to Figs. 1 and 1a, I have shown portions of a knitting machine having upper and lower warp beams B and B'. Yarn webs Y and Y' are drawn from the beams B and B' over tension rolls or bars 10 and 11 and thence to a flat knitting mechanism K (Fig. 1a) which may be of any usual commercial form and which in itself forms no part of my present invention.

Springs 12 and 14 (Fig. 1) provide the usual

tension on the bars 10 and 11, and this tension may be adjusted by nuts 15 and lock nuts 16. The tension bars 10 and 11 yield slightly during the knitting cycle to equalize the strains arising in the knitting operation.

My improved let-off mechanism per se is constructed as a self-contained unit within a casing C (Fig. 3) having a removable cover C'. One unit U is provided for the upper warp beam B, and a second unit U' is provided for the lower warp beam B'. These units are identical, and a description of the upper unit U will apply equally to the lower unit U'. The unit U is shown in an inclined position, but the inclination is merely to facilitate access to certain parts.

Power for continuously operating the let-off units is preferably derived from the usual cam shaft 20 (Fig. 1a), which may be continuously rotated by a motor M through one or more driving belts 22.

A sprocket 24 on the cam shaft 20 is connected by a chain 25 to a sprocket 26 on a shaft 27 rotatable in bearings on the frame F of the machine. An additional sprocket on the shaft 27 and of the same size as the sprocket 26 is connected by a chain 28 and sprocket 29 to a power shaft 30 in the lower let-off unit U', and a third sprocket on the shaft 27 and of the same size as the sprocket 26 is connected by a chain 32 and sprocket 33 (Fig. 3) to a power shaft 34 in the upper let-off unit U.

The power shafts 30 and 34 are thus continuously rotated and in predetermined speed relation to the rotation of the cam shaft 20 which controls the timing of the knitting mechanism K.

The power shaft 34 (Fig. 2) is connected by spiral gears 36 and 37 to a hollow sleeve 38 having a clutch member 40 formed at one end thereof. The sleeve 38 is rotatable in fixed thrust bearings 42, and the member 40 is continuously rotated at constant speed.

A worm 50 (Fig. 2) is mounted on a worm shaft 51, which is rotatable in a fixed bearing 52 and also in a sleeve 53 which is axially movable but non-rotatable in a fixed bracket 54. This sleeve 53 may be secured in axially adjusted position by a clamping screw 55. The shaft 51 extends outward through the end of the casing C and may be turned manually when desired.

The worm 50 meshes with a worm gear 60 mounted on a stud 61 fixed in the casing C, and a gear 62 is rotatable with the worm gear 60. The gear 62 engages a gear 64 on the yarn beam shaft 65. The shaft 65 is rotatable in fixed thrust bearings 66 (Fig. 3) in the machine frame F and supports and rotates a yarn beam B (Fig. 1).

Rotation of the worm 50 will thus rotate the yarn beam B and cause the yarn web Y to be let off.

The provision for rotation of the worm 50 embodies the novel tension-control feature of my invention and will now be described.

A non-rotatable brake member 70 (Fig. 2) is mounted on the sleeve 53 and is of similar section to the rotated driving or clutch member 40 previously described. The worm shaft 51 is slideable in its bearings 52 and 53 and has a double 10 clutch member or runner 75 fixed at its right-hand end, as viewed in Fig. 2. This runner 75 is positioned between the rotating clutch member 40 and the fixed brake member 70 and with limited clearance relative to each. When the machine is in operation, all of these members are submerged in relatively heavy transmission oil.

With this construction, the runner 75 will be rotated by the rotating clutch member 40 through the drag or pull of the oil film between these parts, and the runner 75 will be correspondingly retarded by the oil film between the runner 75 and the fixed brake member 70. The resultant rotating effect on the runner 75 obviously depends on the exact axial position and clearance of the runner relative to the members 40 and 70.

I will now describe the device which I have provided for determining this axial position.

A rod 80 is freely slideable in the sleeve 38 previously described and at its left-hand end is seated in a center hole in the end of the worm shaft 51. The right-hand end of the rod 80 is associated with a piston 82 slideable in a cylinder or sleeve 84.

A spring 85 is mounted in the cylinder 83 and engages the piston 82 at its left-hand end, while the right-hand end of the spring engages a plate 87 abutting the inner end of an adjusting screw 88 which has a graduated knob 89 secured thereon by a lock nut 90. The screw 88 is also threaded in a cap 92, which in turn is threaded on the outer end of the cylinder 83.

The inner end of the cylinder 83 is threaded at 93 to receive the hub 94 of a worm wheel 95. The axial position of the cylinder 83 is determined by engagement of the right-hand end of the hub 94 with the inner face of the fixed bearing 84.

Operation

The operation of the let-off mechanism as thus far described will now be clearly evident.

The clutch member 40 is continuously rotated at constant speed in predetermined relation to the speed of the cam shaft 20, and simultaneously rotates the runner 75 and the worm 50 at a reduced speed determined by the oil friction or drag, which in turn is dependent on the axial position of the runner 75 relative to the clutch member 40 and to the brake member 70.

The pull of the yarn web Y tends to rotate the worm gear 60 anti-clockwise and by direct push on the worm 50 tends to shift the shaft 51 and runner 75 to the right and to further compress the spring 85. This tends to increase the friction pull and the speed of rotation of the worm shaft 51.

The spring 85 acts continuously and directly through the piston 82 and rod 80 to try to shift the runner 75 to the left in Fig. 2, thus increasing the braking effect, decreasing the driving tension, and slowing down the rotation of the runner 75 and worm 50.

If the tension in the yarn web Y is increased, it will thus shift the worm 50 and runner 75 to the right in Fig. 2 and will thereby increase the

liquid drag or pull of the clutch member 40 and correspondingly increase the speed of rotation of the worm 50. This increases the rate of let-off and promptly relieves the increased yarn web tension. As the excess yarn tension is relieved, the spring 85 returns the runner 75 to its normal running position and balanced clearance. If the yarn web becomes slack, the spring 85 shifts the runner 75 to the left to decrease the rate of let-off.

The yarn web is thus let off at a substantially constant speed and in definite relation to the speed of the cam shaft, but at the same time the rate of let-off will be temporarily increased or decreased to correct variations in web tension as they may occur. As the yarn web is let off in the direction of yarn pull, the load on the tension units U and U' is relatively small.

Adjustment for yarn beam diameter

It will be obvious that the speed of let-off rotation of the yarn beam shaft 65 must be increased as the diameter of the web on the beam decreases, and it will also be obvious that the tension of the yarn web transmitted through the gears 64 and 62 and the worm gear 60 to the worm 50 will act at an increasing mechanical disadvantage, as the decrease in diameter of the yarn web correspondingly reduces the radius of the point of application of the yarn tension to the gear train.

In order to offset these dual and cumulative effects, I have made special provision for reducing the compression of the spring 85 as the diameter of the web on the yarn beam decreases, and I will now describe the devices by which this is accomplished.

The worm wheel 95 (Fig. 2) previously described is engaged by a worm 100 (Fig. 3) mounted on a worm shaft 101 rotatable in fixed bearings in the casing C and cover C'. The front end of the shaft 101 extends through the cover and may be slotted so that it can be conveniently turned for manual adjustment.

A ratchet 103 (Fig. 2) is fixed on the shaft 101 and is engaged by a pawl 105 mounted on a forked or slotted arm 106 which embraces the shaft 101 and is both angularly and radially movable relative thereto. A spring 107 yieldingly holds the pawl 105 in engagement with the ratchet 103.

The upper end of the arm 106 is pivoted at 110 to a link 111 having its left-hand end portion (Fig. 2) slotted at 112 to embrace a cam shaft 114. A cam 115 is mounted on the shaft 114 and the link 111 has a pin 117 which is held in engagement with the cam 115 by a tension spring 118.

As the cam 115 rotates, the ratchet 103 will be correspondingly advanced, thus giving the worm gear 95 an angular movement which will allow the cylinder 83 to slide further toward the right in Fig. 2, and correspondingly reducing the compression of the spring 85.

When the pin 117 passes off of the point of the cam 115, the arm 106 and associated pawl 105 receive a return or idle movement to the right until the arm engages the end of an adjusting screw 120. The amount of feed of the ratchet 103 for each oscillation of the arm 106 is determined by the setting of the adjusting screw 120. The further the screw is advanced into the casing C, the less teeth the pawl 105 will take on each oscillation.

Provision is made for raising the pawl 105 out of engagement with the ratchet 103 when it is desired to turn the shaft 101 manually backward

for adjustment or resetting. For this purpose, a collar 122 (Fig. 2) is mounted on a stud 123 extending freely upward through an upper wall of the casing C and having a knob 125 threaded thereon. The link 111 is freely slidable through the collar 122. Manual rotation of the knob 125 will raise the collar 122, which in turn will lift the link 111 and raise the pawl 105 to clear the ratchet 103 and thus permit manual reverse movement of the worm shaft 101.

The cam shaft 114 (Fig. 2) has a ratchet 130 engaged by a feed pawl 131 and a holding pawl 132, each held in yielding engagement with the ratchet by a spring 133. The holding pawl 132 is mounted on a fixed stud 135, but the feed pawl 131 is pivoted at 136 to a feed lever 137 which is mounted to swing about the axis of the cam shaft 114.

The feed lever 137 (Fig. 2) is engaged by a cam 140, which is mounted on the yarn beam shaft 65 and rotates with the gear 64. A spring 142 tends to move the lever 137 toward the cam 140, and the extent of this movement is determined by an adjusting screw 145 threaded in the casing C and engaging a laterally projecting arm 146 on the lever 137. The extent of idle return movement of the feed pawl 131 is determined by the adjustment of the screw 145, as in the similar ratchet feed previously described.

Each complete revolution of the yarn beam shaft 65 and its associated yarn beam will rotate the cam 140 and give the feed lever 137 and feed pawl 131 a feeding movement, the extent of which is determined by the adjusting screw 145. Each complete revolution of the ratchet 130 and associated cam shaft 114 and cam 115 will give the arm 106 and feed pawl 105 an oscillating feeding movement, which in turn is determined by the setting of the adjusting screw 120. Such movement, as previously described, will effect progressive reduction of the compression of the spring 85, so that progressive reduction in yarn web diameter will effect axial shifting of the runner 75 and a corresponding increase in runner speed.

The initial compression of the spring 85 may be determined by turning the graduated disc 89, and the rate of correction for reduction in yarn web diameter may be experimentally determined by the setting of the adjusting screws 145 and 120 and with due regard to the size or diameter of the yarn.

It should be particularly noted that the force which turns the runner 75 and thus acts to let off the yarn web, is not a direct force, but is a differential force determined by the fluid friction pull of the constantly rotating clutch member 40, and the fluid friction drag of the fixed brake member 70.

It is found in actual use that ordinary changes in temperature or viscosity of the transmission oil do not materially effect the operation of this let-off mechanism, as the differential pull which rotates the worm 50 is substantially independent of such temperature or viscosity changes.

Having thus described my invention and the advantages thereof, I do not wish to be limited to the details herein disclosed, otherwise than as set forth in the claims, but what I claim is:

1. A let-off mechanism for a textile machine having a rotated yarn supply comprising a driven shaft, speed-reducing connections between said shaft and said rotating yarn supply, a continuously rotated driving shaft, a clutch member thereon, an opposed stationary brake

member, a runner connected to said driven shaft and positioned between said rotating clutch member and said stationary brake member, said shafts and associated parts being immersed in transmission oil, and said runner and driven shaft being rotated by the excess of the oil-transmitted pull of the clutch member over the oil-transmitted drag of the brake member.

2. A let-off mechanism for a textile machine having a rotated yarn supply comprising a driven shaft, speed-reducing connections between said shaft and said rotating yarn supply, a continuously rotated driving shaft, a clutch member thereon, an opposed stationary brake member, a runner connected to said driven shaft and positioned between said rotating clutch member and said stationary brake member, said shafts and associated parts being immersed in transmission oil, said runner and driven shaft being rotated by the excess of the oil-transmitted pull of the clutch member over the oil-transmitted drag of the brake member, and means to vary the proportionate clearance of said runner relative to said clutch member and said brake member.

3. A let-off mechanism for a textile machine having a rotated yarn supply comprising a driven shaft, speed-reducing connections between said shaft and said rotating yarn supply, a continuously rotated driving shaft, a clutch member thereon, an opposed stationary brake member, a runner connected to said driven shaft and positioned between said rotating clutch member and said stationary brake member, said shafts and associated parts being immersed in transmission oil, said runner and driven shaft being rotated by the excess of the oil-transmitted pull of the clutch member over the oil-transmitted drag of the brake member, the spacing of said clutch member and said brake member being axially fixed, and said runner being axially shiftable between said members.

4. The combination in a let-off mechanism as set forth in claim 3, in which means is provided to shift the runner axially in response to changes in let-off tension in said machine.

5. The combination in a let-off mechanism as set forth in claim 3, in which means is provided to shift the runner axially in response to changes in let-off tension in said machine, and in which means is provided to vary the amount of axial shift of said runner for a given change in yarn tension in predetermined relation to the reduction in diameter of said yarn supply.

6. The combination in a let-off mechanism as set forth in claim 3, in which means is provided to shift the runner axially in response to changes in let-off tension in said machine, and in which said latter means includes a spring resistant to axial shifting of the runner toward the rotating clutch member.

7. The combination in a let-off mechanism as set forth in claim 3, in which means is provided to shift the runner axially in response to changes in let-off tension in said machine, and in which said latter means includes a spring resistant to axial shifting of the runner toward the rotating clutch member, and means to decrease the resistance of the spring to such axial shifting of the runner for a given change in yarn tension.

8. The combination in a let-off mechanism as set forth in claim 3, in which means is provided to shift the runner axially in response to changes in let-off tension in said machine, and in which said latter means includes a spring resistant to

axial shifting of the runner toward the rotating clutch member, and means to decrease the resistance of the spring to such axial shifting of the runner for a given change in yarn tension and in proportion to the reduction in diameter of the yarn supply.

9. The combination in a let-off mechanism as set forth in claim 3, in which means is provided to shift the runner axially in response to changes in let-off tension in said machine, and in which said latter means includes a spring resistant to axial shifting of the runner toward the rotating clutch member, and means to decrease the resistance of the spring to such axial shifting of the runner for a given change in yarn tension and in proportion to the reduction in diameter of the yarn supply, and said latter means being directly actuated with said rotating yarn supply.

10. The combination in a let-off mechanism as set forth in claim 3, in which means is provided to shift the runner axially in response to changes in let-off tension in said machine, and in which said latter means includes a spring resistant to axial shifting of the runner toward the rotating clutch member, manual means to ad-

5

just the initial resistance of said spring, and means to decrease the resistance of the spring to such axial shifting of the runner for a given change in yarn tension and in proportion to the reduction in diameter of the yarn supply.

11. The combination in a let-off mechanism as set forth in claim 10, in which means is provided to vary the rate of decrease of spring resistance for a given change in the diameter of the yarn supply.

GEORGE E. CLENTIMACK.
